Patented Dec. 28, 1920.

UNITED STATES PATENT OFFICE.

EDWARD L. MONNOT, OF CANTON, OHIO.

ELECTROMECHANICAL JACK.

1,363,991.

Specification of Letters Patent. Patented Dec. 28, 1920.

Application filed January 15, 1920. Serial No. 351,708.

To all whom it may concern:

Be it known that I, EDWARD L. MONNOT, a citizen of the United States, and resident of Canton, in the county of Stark and State 5 of Ohio, have invented certain new and useful Improvements in Electromechanical Jacks, of which the following is a specification.

The improvement relates to lifting jacks 10 for dental, surgical and barber chairs, and the object of the improvement is to combine an electric motor directly with lifting mechanism in the base of a chair so that the chair may be raised and lowered by 15 pressing one or the other of two adjacent pedals.

The object of the invention, thus set forth in general terms, is attained by the construction and arrangement illustrated in the 20 accompanying drawings forming part hereof, in which—

Figure 1 is a vertical section of the base of a chair showing the motor and the lifting mechanism embodied therein; and 25 Fig. 2 an inner end elevation of the motor showing the case in section as on line 2—2, Fig. 1.

Similar numerals refer to similar parts throughout the drawings. 30 Upon the circular base plate 1 of the chair is rotatably mounted the base standard 2, the intermediate standard 3 and the chair standard 4, which standards telescope and are extensibly guided one within the other 35 in the usual manner.

A pivot post 5 is centrally mounted on the base plate 1, upon which post is journaled the hub 6 of the cylindric pulley 7 having the flared friction flanges 8 annularly arranged on its periphery.

The lower side of the pulley preferably rides upon ball bearings 9, and the disk plate 10 may be secured to the top of the pivot post to stop an upward movement of 45 the pulley thereon.

The upright cylindric screw 11 is mounted on the hub of the pulley and may be secured thereto by the annular flange 12 and set screw 13; upon the outer side of which 50 cylindric screw is operatively mounted the nut 14 secured to the lower end of the intermediate standard 3, and inside of the cylindric screw is operatively mounted the screw stem 15 secured to the upper end of 55 the chair standard 4; so that a rotation of

the cylindric screw raises and lowers the extensible standards in a well known manner.

A motor 16 is mounted on the bottom plate 17 of the V-shaped swinging carriage having its side plates 18 and 18^a pivoted at 60 19 and 19^a to the upper ends of the standards 20 which project upward through slots 21 and 21' in the carriage bottom from the supporting plate 22 which plate is extended laterally from one side of the base stand- 65 ard 2.

The upright switch arm 23 is mounted outside the outer side plate 18 upon an extension of the pivot 19, and operates between the opposite pairs of jaws 24 for closing the 70 electric circuit to operate the motor. The downward extension 25 of the switch arm is pivoted to the stem 27 of the inverted T-lever 28, on the arms 29 of which lever are provided 75 pedals as 30 extending laterally through apertures as 31 in the side of the motor case 32, which case may be secured to the base standard 2 by screws 33.

The inverted T-lever is fulcrumed upon the pivot 34 projecting from the side plate 80 18 of the carriage and upon the outer end of this pivot is fixed the head 35 to which is secured the upright spring 36. The upper end of this spring operates in the slotted boss 37 on the side of the lever stem 27, to 85 normally hold the same in vertical position; and the adjustable stop screws 38 are provided in the bosses 39, on the outer side plate of the carriage, to limit the movement of the T-lever with reference to the swinging 90 carriage.

The pendent spring 40 is secured at its upper end to the boss 41 on the inner side of the supporting standard 20, and its lower free end operates in the slotted boss 42 on 95 the carriage bottom to normally hold the same in central pendent or horizontal position; and the spring 40 is of such greater strength than the spring 36, that when one of the pedals 30 is depressed, the swinging 100 platform will remain in normal position while the stem of the T-lever is deflecting the weaker spring 36 until the opposite arm 29 impinges the corresponding stop screw 38; whereupon a further depression of the 105 same pedal swings the motor carriage upon its pivotal supports 19.

In the normal position of the parts, the conical friction pinion 43 on the inner end of the motor shaft is positioned freely mid- 110

way between the flared friction flanges 8 on the cylindric pulley 7, as shown in Fig. 1; and it is evident that a swinging or tilting of the motor carriage will bring the pinion 5 into frictional engagement with one or the other of the flared flanges for operating the lifting mechanism in one direction or the other.

For operating the motor to raise the chair 10 standards, one of the pedals is depressed by the foot and the T-lever is turned in one direction against the resistance of the relatively weak spring 36 until the switch arm enters between one of the pairs of jaws 24 15 thus closing the circuit and starting the motor; whereupon the opposite arm 29 of the T-lever impinges the corresponding stop screw 38 and a further depression of the same 20 pedal swings the motor carriage until the pinion 43 impinges the corresponding friction flange for operating the lifting mechanism to raise the chair; and it is obvious that a depression of the other pedal in like manner will first start the motor and then 25 reversely operate the lifting mechanism to lower the chair.

Means are provided for stopping the operation of the lifting mechanism as the chair standards approach the limit of their proper 30 movement; and such means may comprise the bell crank 44 mounted in the base standard 2 having one arm 45 protruding into the vertical slot 46 in the intermediate standard, and the other arm 47 depending 35 from a pivotal connection with the rod 48 which slidably extends through the guide eye 49 on the upper end of the carriage side plate 18.

Stop nuts 50 are adjustably spaced and locked on the rod 48 on each side of the 40 guide eye, so that when the ends of the slot 46 impinge the arm of the bell crank 44, the rod 48 will be moved endwise and the corresponding stop nut thereon will operate against the guide eye 49 to swing the motor 45 carriage into normal position, which frees the friction pinion from contact with the pulley flange and stops the operation of the lifting mechanism.

The automatic and positive action of stopping means, raises the pedal which has been 50 depressed, and thus informs the operator that the limit of the movement of the chair standards has been reached, so that the foot can be removed from the pedal, whereupon

the action of the spring 36 returns the switch 55 arm to normal position which opens the circuit and stops the motor.

I claim:

1. Lifting mechanism including an operating pulley having two peripheral friction flanges thereon, a swinging carriage with an electric motor thereon having a friction pinion normally located freely between the friction flanges, two pairs of switch jaws in the motor circuit on the carriage and a switch arm normally located freely between the jaws, and means for initially swinging the switch arm into either pair of jaws for starting the motor, and subsequently swinging the motor carriage to contact the friction pinion with one of the friction flanges for operating the lifting mechanism one way or the other.

2. Lifting mechanism including an operating pulley having two peripheral friction flanges thereon, a spring controlled swinging carriage with an electric motor thereon having a friction pinion normally located freely between the friction flanges, two pairs of switch jaws in the motor circuit on the carriage and a switch arm normally located freely between the jaws, and spring controlled means for initially swinging the switch arm into either pair of jaws for starting the motor, and subsequently swinging the motor carriage to contact the friction pinion with one of the friction flanges for operating the lifting mechanism one way or the other.

3. Lifting mechanism including an operating pulley having two peripheral friction flanges thereon, a swinging carriage with an electric motor thereon having a friction pinion normally located freely between the friction flanges, two pairs of switch jaws in the motor circuit on the carriage and a switch arm normally located freely between the jaws, means for initially swinging the switch arm into either pair of jaws for starting the motor, and subsequently swinging the motor carriage to contact the friction pinion with one of the friction flanges for operating the lifting mechanism one way or the other, and means actuated by the lifting mechanism for stopping the same as it approaches the limit of its movement in either direction.

EDWARD L. MONNOT.
